UNITED STATES PATENT OFFICE.

LAMBERT J. BORDO, OF ROSLYN, PENNSYLVANIA.

BLOW-OFF VALVE.

1,085,013.

Specification of Letters Patent. Patented Jan. 20, 1914.

Application filed October 9, 1911. Serial No. 653,526.

To all whom it may concern:

Be it known that I, LAMBERT J. BORDO, a citizen of the United States of America, residing in Roslyn, county of Montgomery, 5 State of Pennsylvania, have invented a certain new and useful Improvement in Blow-Off Valves, of which the following is a true and exact description, reference being had to the accompanying drawings, which form a 10 part thereof.

My present invention consists in an improved valve particularly intended for use as a blow off valve for locomotive and other boilers, pulp digesters and analogous devices.

The objects of the invention are to provide a valve suitable for the use specified which is inherently strong and durable; and simple in construction, and which is so constructed 20 that the damage done to the valve by the erosive action of the fluid passing through the valve is reduced to a practical minimum; and in which the port sealing parts of the valve may be readily and comparatively inexpensively renewed from time to time as 25 conditions may require.

The various features of novelty which characterize my invention are pointed out with particularity in the claims annexed to 30 and forming a part of this specification. For a better understanding of the invention, however, and the advantages possessed by it, reference should be had to the accompanying drawings and descriptive matter in which I 35 have illustrated and described several forms in which my invention may be embodied.

Of the drawings, Figure 1 is a sectional elevation of a preferred form of valve constructed in accordance with the present invention, and shown in the closed position, the section being taken on the line 1—1 of Fig. 4. Fig. 2 is a side or edge elevation of the valve member proper of the valve shown in Fig. 1. Fig. 3 is a front elevation of the 40 valve member shown in end elevation in Fig. 2. Fig. 4 is a section through the valve casing taken on the line 4—4 of Fig. 1, the valve proper being shown in full lines.

Fig. 5 is a sectional elevation taken similarly 45 to Fig. 1 showing a modified form of valve casing which may be employed. Fig. 6 is a view taken similarly to Fig. 1, illustrating a valve casing modification; and Fig. 7 is a view of a portion of an angle valve having a 50 valve casing modification illustrated by Fig. 6.

In the drawings, and referring first to the constructions shown in Figs. 1—5, the valve casing or body A shown in Figs. 1 and 4 is formed with a valve chamber A' and inlet and outlet ports or passages A² and A³, respectively, communicating therewith. The valve casing AB shown in Fig. 5 differs from that shown in Figs. 1 and 2 only in that the casing body AB of Fig. 5 has the outlet passage A³⁰ in alignment with the inlet passage A² while the valve shown in Figs. 1 and 2 is an angle valve and the inlet and outlet passages A² and A³ are at right angles to each other. The valve casing proper, in each 55 form, is open at its upper end, the opening being normally closed by a bonnet or cap member B. The valve seat proper surrounds the inlet passage A² and is formed by an annular member C of suitable material, such as copper, brass or tough non-metallic substance, such as vulcanized fiber, hard rubber or the like, the material employed varying with the conditions of use. The valve seat member C is received in a channel A⁴ formed 60 for the purpose in the valve casing.

The valve member proper, or gate, controlling the flow through the valve, is in the form of a block D shown as hollow and open at its lower end but closed at its upper end 65 except for a threaded aperture D' receiving the threaded portion E' of the valve spindle E. The latter in the form shown is journaled for rotative but not for axial movement in the cap or bonnet B, and a stuffing 70 box B' may be provided, as shown, to prevent leakage along the spindle. The gate D is provided at its lower end with front and back depending aprons or flanges D³. Alined apertures D⁴ formed in these flanges D³ are 75 adapted to register with the inlet passage A² when the valve is open as shown in Fig. 5. The whole gate, including the flange extensions D³, is of a length rather more than double the diameter of the valve seat 80 member C. To force the gate D against the valve seat C in order to effectually cut off communication between the inlet passage A² and the valve chamber A' when the valve is closed, the valve casing has formed on its 85 side walls A⁵ inclined or wedge shoulders G, and the gate D is formed with coöperating inclined or wedge shoulders D⁶ at its opposite edges. These coöperating wedge surfaces serve to wedge or cam the gate D 90 tightly against the valve seat member C when the valve is in the closed position.

shown in Fig. 1. To limit the movement of the gate away from the valve seat member C, when the valve member is out of the closed position, I prefer to form on the side walls A⁵ of the valve casing straight shoulders F which extend parallel to the valve spindle E and coöperate with corresponding shoulders D⁶ on the gate D. In the preferred constructions shown in Figs. 1 to 5, 5 the gate D is formed at each side edge with two sets of shoulders D⁵ and D⁶ so that the gate is reversible and may have either flat side turned toward and coöperating with the valve seat C.

10 It will be apparent without further explanation that in the valve construction shown in Figs. 1-5 inclusive, the gate member is readily and quickly movable from the wide open to the fully closed position by giving the spindle E a few turns in its bearing in the cap B. When the gate is moved down into its seating position, the wedging provisions between the valve casing and the gate insure the proper pressure of the latter 15 against the seat C to make a tight joint and avoid leakage, notwithstanding the fact that the inlet pressure in the chamber A² acts directly against the gate D in a direction tending to move it away from its seat. When the 20 valve is wide open, discharge takes place freely from the inlet passage A² into the chamber A' in the gate D through the adjacent port D³, passing from this chamber through the open lower end of the gate, in 25 the construction shown in Fig. 1, into the outlet passage A³, and through the alined passage D³ at the outer side of the gate into the outlet passage A³⁰ in the construction shown in Fig. 5. The valve seat member C 30 is engaged and held in place by the gate D when the valve is open, as well as when it is closed. The valve seat member C and the portion of the gate D engaging the valve seat when the valve is closed, and also the 35 coöperating guiding and wedging surfaces F and G and D⁵ and D⁶ are all out of the direct path of the flow when the valve is open, and in addition the valve seat member C and the adjacent surface of the gate D are 40 then covered, the first by the lower portion of the gate D, the other by the adjacent side of the valve casing.

The wearing away or scoring of the parts 45 directly subjected to the erosive action of the fluid discharged in consequence does not directly interfere with the operation of the valve and the proper seating of the gate member against the valve seat. The valve seat member C may readily be reversed 50 when the side originally presented to the valve becomes worn or otherwise injured, and may readily be replaced by another when this is necessary or desirable. The gate D can also be readily reversed when 55 the side originally engaging the valve seat

becomes worn away, and the gate member is inherently relatively inexpensive in construction, thus involving a comparatively low cost of renewal, when renewal becomes desirable. The formation of the wedging and 60 guide surfaces on the wall of the valve casing at the opposite sides of the valve seat not only removes these surfaces from the direct path of the fluid discharged but gives an inherently stronger construction than 65 would be had if the gate were wedged to its seat, for instance, by engagement of wedging surfaces formed on the front side of the gate and the adjacent side of the valve casing. The outer casing wall A⁶ forms a barrier 70 reducing the liability of injury in case the gate proper breaks in two, or breaks loose from its guiding and wedging engagement with the sides of the valve casing. The internal machining of the valve casing 75 required is very slight, since it consists only in boring out the channel A⁴ with a suitable boring bar or like device, and the planing of the guiding and wedging surfaces F 80 and G.

85 While with my improved construction it is, in general, immaterial whether the inlet and outlet passages of the valve casing are alined as shown in Fig. 5 or are at angle as shown in Fig. 1, it is to be observed that the 90 conditions of use frequently make the latter arrangement desirable, and that insofar as I am aware, the combination herein disclosed is the first practically operative angle 95 blow off gate valve for use under the extremely severe conditions to which blow off 100 valves are frequently subjected.

105 In many cases I consider it desirable to form the valve casing body as shown in Figs. 6 and 7, with the portion A⁷ of the valve casing surrounding the inlet passage and supporting the valve seat member C, separable from the remainder of the valve casing body connected thereto, as by means 110 of the threaded joint A⁸. By dividing the valve casing body in this manner I facilitate and simplify the formation of the channel A⁴ receiving the valve seat member C, particularly in valves of the smaller sizes. This construction also makes it possible 115 to fit into similar valve casing bodies, parts A⁷ made in a variety of forms, with respect to the provisions for connecting the inlet side of the valve casing to the boiler, digester or the like device with which it is to be employed. This reduces the quantity of material necessarily or desirably kept in stock.

120 While in accordance with the provisions of the statutes I have illustrated and described the best forms of my invention now known to me, it will be apparent to those skilled in the art that changes may be made in the form of the apparatus disclosed without departing from the spirit of my invention.

tion, and that under certain conditions certain features of the invention may be used with advantage without a corresponding use of other features.

5 Having now described my invention what I claim as new and desire to secure by Letters Patent, is:

1. In a valve of the kind described, the combination of a body member formed with 10 a port and with a valve seat at one end of, and surrounding said port, and with guide surfaces at opposite sides of said port, and a reversible valve member slidably movable transversely to said seat to open and close 15 said port, said valve member having two opposed faces either of which may be turned toward said seat and having two sets of guide surfaces, of which one or the other set, depending on which valve face is turned to- 20 ward said seat, engage the guide surfaces of the casing body to draw said valve against said seat with a wedging action as the valve member is moved into position to close said port.

25 2. In a valve of the kind described, the combination of a body member formed with a port and with a valve seat at one end of, and surrounding said port and guide surfaces at opposite sides of said port, and a reversible member slidably movable trans- 30 versely to said seat for opening and closing said port, said valve member having two opposed faces either of which may be turned toward said seat and having two sets of 35 guide surfaces of which one or the other set, depending on which valve face is turned toward said seat, engage the guide surfaces of the casing body to draw said valve against said seat with a wedging action when the 40 valve member is moved into position to close said port, and said valve member having two extensions, one for each face, for covering said seat, when the valve member is moved into position to open said port, said 45 extensions being spaced apart and each being formed with an aperture registering with said port when the latter is open.

3. In a valve of the kind described, the combination with a casing body formed with 50 a valve chamber and with inlet and outlet ports opening to said chamber at an angle

to each other and provided with a valve seat surrounding the inner end of said inlet port and with guide surfaces at opposite sides of said port, of a reversible valve member located in said valve chamber and slidably movable transversely to said seat to open and close said inlet port, said valve member having two opposed faces either of which may be turned toward said seat and having two sets of guide surfaces of which one or the other set, depending on which valve face is turned toward said seat, engage the guide surfaces of the casing body to draw said valve against said seat with a 65 wedging action when the valve member is moved into position to close said port, said valve member being formed with an opening extending into it between said faces at the end of the member adjacent the outlet pas- 70 sage and being formed with ports leading from said space, one to each of said faces, and adapted to register with the first mentioned port when the valve member is moved into position to open the latter.

4. As an article of manufacture, a reversible valve gate having two opposed valve seat engaging faces and formed at each of an opposed pair of edges with two guide surfaces one inclined to one and the other to 80 the second of said faces.

5. As an article of manufacture, a reversible valve gate having two opposed valve seat engaging faces and formed at each of an opposed pair of edges with two opposed guide 85 surfaces one inclined to one and the other to the second of said valve faces and with two opposed guide surfaces one parallel to one and the other parallel to the second of said 90 valve faces.

6. As an article of manufacture, a reversible valve gate having two opposed valve seat engaging faces and having a space opening into it between said faces from one end of the gate and having ports opening from said 95 space one to each of said faces and having wedging guide surfaces formed at its opposite side edges.
